CARL H. BISSELL, OF SYRACUSE, NEW YORK, ASSIGNOR TO CROUSE-HINDS COMPANY,
OF SYRACUSE, NEW YORK, A CORPORATION OF NEW YORK.

ELECTRICAL COUPLING.

974,462.

Specification of Letters Patent.

Patented Nov. 1, 1910.

Application filed January 27, 1910. Serial No. 540,350.

To all whom it may concern:

Be it known that I, CARL H. BISSELL, of Syracuse, in the county of Onondaga and State of New York, have invented a certain 5 new and useful Electrical Coupling, of which the following is a specification.

My invention relates to electrical couplings, and the object thereof is to provide a durable, simple and highly efficient device 10 for connecting two conductors to each other, or one conductor to a suitable support.

The invention consists in the combinations and constructions hereinafter described and particularly pointed out in the 15 claims.

In the accompanying drawings which illustrate one exemplification of my invention:—Figure 1 is an elevation, partly broken away and in section, of this coupling, 20 and two conductors connected thereby. Fig. 2 is an end elevation, partly in section, of said parts. Fig. 3 is an end elevation, partly in section, of the detached coupling, one of the sections of the band member being 25 shown as disengaged from the nut and swung upwardly. Fig. 4 is a side elevation of one of the members of the coupling.

This coupling comprises generally a sectional band or strap member, a main member having means coacting with the band or strap member for clamping a conductor passing through the bore of the band or strap member, said main member also having means for engaging a second conductor or support, and a nut for coacting with the two members.

In the illustrated embodiment of my invention the band or strap member comprises two segmental sections 1 and 2 pivotally connected at corresponding ends to each other, as at 3, and provided at their free ends with opposing laterally extending externally threaded projections 4 and 5. The projections 4 and 5 form in effect a 45 sleeve extending laterally from the bore of the band member, and contiguous portions of the projections are provided with complementary recesses forming slots 6 extending laterally from the bore of said sleeve.

50 The main member of the coupling is provided at one end with a head 7 having an arcuate face 8 for engaging a conductor 9, is provided at its opposite end 10 with means

for engaging a second conductor or support 11, and is provided intermediate of the head 55 7 and the end 10 with a shank 12 hereinafter particularly described.

In the present exemplification of my invention the means associated with the end 10 of the main member for engaging a second 60 conductor or support 11 comprises a compressible sleeve 13 having a tapering periphery complementary to a socket or bore in the end 10, and a nut 14 formed with a threaded bore engaging external threads on 65 the end 10, and with a shoulder 15 engaging the end of the sleeve 13 for forcing the latter into the socket and thereby contracting the sleeve 13 about the end of the conductor or support 11.

The head 7 is designed to operate between the sections 1 and 2 of the band member or within the bore of said band member, and is disposed with its greater length parallel to the axis of such bore, and the face 8 thereof 75 is designed to coöperate with the inner surfaces of the sections 1 and 2 so that the conductor 9 will be firmly engaged substantially at all points about the part of its periphery located between said sections 1 and 2. 80

The nut 16 associated with the band and main members of the coupling serves to hold these parts in clamping position and to secure one of the sections of the band member against separation from the main member of the coupling while permitting the movement of the other section of the band member about the pivot 3 to admit the conductor 9 within the bore of the band member, and said nut when properly adjusted 90 admits of the band member being entirely separated from the main member. In the accompanying drawing this nut 16 engages the external threads on the end 10, and the threads of the projections 4 and 5 and its 95 upper edge coacts with shoulders 17 which are provided on the head 7 and project laterally through the slots 6 and beyond the sleeve formed by the projections 4 and 5. Consequently, as the nut 16 is screwed toward the head 7 the face 8 and the inner surfaces of the sections 1 and 2 of the band member are forced into firm contact with the conductor 9 passing through the bore of said band member. 100

The inner faces of the projections 4 and

5 and the coacting surfaces of the shank 12 are preferably so constructed that a nut of uniform bore may be employed for engaging both the end 10 of the main member and one 10 or both of the projections 4 and 5 when the latter are in contact with the shank 12. To this end a part of the shank 12 is made of reduced size, and the inner faces of the projections 4 and 5 are shaped to conform to 15 the contiguous surface of said reduced part. In the exemplification of my invention shown in the accompanying drawing, the reduced portion of the shank 12 is formed by making a part of the shank of less diameter than the nut 10 and substantially cylindrical in form, and the projections 4 and 5 are substantially semi-circular in cross section and their inner faces closely fit the surfaces of the shank with which they come 20 in contact. Consequently the reduced portion of the shank 12 extends through and fits the bore of the sleeve formed by the projections 4 and 5.

In order that one of the sections of the 25 band member may be swung upwardly on its pivot 3 while the remaining section is coupled by the nut 16 to the main member of the coupling, the projections 4 and 5 are of unequal length, the projection 5 being 30 longer than the projection 4, and remaining in engagement with the nut 16 after the same has been turned from the head 7 sufficiently to disengage the projection 4 from 35 said nut. By additionally turning the nut 16 in the same direction the projection 5 will be disengaged from said nut and the band member may then be wholly disconnected from the main member of the coupling. In the preferable construction of this coupling 40 lengthwise edges or surfaces of the projections 4 and 5 between the recesses forming the slots 6 and the ends of said projections are engaged with each other to prevent movement or springing of said projections 45 relatively to each other especially when the nut 16 is turned. Moreover, to prevent twisting on the shank 12 of the sleeve formed by the projections 4 and 5, one side of said shank beneath the projection 4 is 50 unreduced in diameter and is provided with lengthwise shoulders 18 which are engaged by the opposing surfaces of the projection 5.

What I claim is:

1. In an electrical coupling, a band member comprising two sections pivotally connected to each other at corresponding ends and provided at their opposite ends with opposing externally threaded projections, a main member having a shank provided with 55 an engaging face for coöperating with the band member, said projections being shaped to embrace a portion of the shank, and a nut for engaging the externally threaded projections and the shank, substantially as and for the purpose specified.

2. In an electrical coupling, a band member comprising two sections pivotally connected to each other at corresponding ends and provided at their opposite ends with opposing externally threaded projections, a 70 main member having a shank provided with an engaging face at one end for coöperating with the band member, the shank having a substantially cylindrical portion, and the inner faces of said projections being shaped 75 to conform to the periphery of the cylindrical portion of the shank, and a nut for engaging the externally threaded projections and the shank, substantially as and for the purpose described.

3. In an electrical coupling, a band member comprising two sections pivotally connected to each other at corresponding ends and provided at their opposite ends with opposing externally threaded projections substantially semi-cylindrical in cross section, a main member having a shank provided with an engaging face for coöperating with the band member, the shank having a cylindrical part of reduced diameter embraced by 90 said projections, and a nut for engaging the externally threaded projections and the shank, substantially as and for the purpose set forth.

4. In an electrical coupling, a band member comprising two sections pivotally connected to each other at corresponding ends and provided at their opposite ends with opposing externally threaded projections, a main member having a shank provided with an engaging face for coöperating with the band member, said projections being shaped to embrace a portion of the shank and having 95 opposing lengthwise surfaces normally engaging each other, and a nut for engaging the externally threaded projections and the shank, substantially as and for the purpose specified.

5. In an electrical coupling, a band member comprising two sections pivotally connected to each other at corresponding ends and provided at their opposite ends with opposing externally threaded projections substantially semi-cylindrical in cross section 110 which in effect form a sleeve when the band member is in clamping position, said projections having opposing lengthwise surfaces normally engaging each other, a main member having a shank provided with a head at one end located within the bore of 115 the band member and coöperating with said band member, the shank having a cylindrical part of reduced diameter embraced by the inner faces of the opposing projections, and a nut for engaging the externally threaded 120 projections and the shank, substantially as and for the purpose described.

6. In an electrical coupling, a band member comprising two sections pivotally connected to each other at corresponding ends 125

and provided at their opposite ends with opposing externally threaded projections, a main member having a shank provided with an engaging face for coöperating with the 5 band member, said projections being shaped to embrace a portion of the shank, and the shank being provided with shoulders projecting laterally beyond said projections, and a nut for engaging the externally threaded 10 projections and said shoulders, substantially as and for the purpose set forth.

7. In an electrical coupling, a band member comprising two sections pivotally connected to each other at corresponding ends 15 and provided at their opposite ends with opposing externally threaded projections having contiguous portions thereof formed with complementary recesses, a main member having a shank provided with an engaging face 20 for coöperating with the band member, said projections being shaped to embrace a portion of the shank, and the shank being provided with shoulders projecting laterally through the recesses beyond said projections, 25 and a nut for engaging the externally threaded projections and said shoulders, substantially as and for the purpose specified.

8. In an electrical coupling, a band member comprising two sections pivotally connected to each other at corresponding ends 30 and provided at their opposite ends with opposing externally threaded projections substantially semi-cylindrical in cross section which in effect form a sleeve when the band member is in clamping position, contiguous portions of the projections being provided with complementary recesses forming opposite slots opening laterally from the bore of the sleeve, and said projections having 35 opposing lengthwise surfaces normally engaging each other, a main member having a shank provided with a head at one end located within the bore of the band member and coöperating with said band member, the shank having a cylindrical part of reduced diameter embraced by the inner faces of the 40 opposing projections, and the shank also having shoulders projecting laterally through the recesses beyond said projections, 45 and a nut for engaging the externally threaded projections and said shoulders, substantially as and for the purpose described.

9. In an electrical coupling, a band member comprising two sections pivotally connected to each other at corresponding ends 55 and provided at their opposite ends with opposing externally threaded projections, a main member having a shank provided with an engaging face at one end for coöperating 60 with the band member, the shank being provided with additional engaging means, and said projections being shaped to embrace a portion of the shank, and a nut for engaging the externally threaded projections and 65 the shank to effect relative movement of the

band and main members, said nut coöperating with one of the externally threaded projections and the additional engaging means of the shank for uniting said projection and shank, substantially as and for the purpose set forth. 70

10. In an electrical coupling, a band member comprising two sections pivotally connected to each other at corresponding ends and provided at their opposite ends with opposing externally threaded projections, a main member having a shank provided with an engaging face at one end for coöperating with the band member, the shank being provided with a threaded portion, and said projections being shaped to embrace a portion of the shank, and a nut for engaging the externally threaded projections and the shank to effect relative movement of the band and main members, said nut coöperating with one of the externally threaded projections and the threaded portion of the shank for uniting said projection and shank, substantially as and for the purpose specified. 75 80 85 90

11. In an electrical coupling, a band member comprising two sections pivotally connected to each other at corresponding ends and provided at their opposite ends with opposing externally threaded projections substantially semi-cylindrical in cross section which in effect form a sleeve when the band member is in clamping position, said projections having opposing lengthwise surfaces normally engaging each other, a main member having a shank provided with a head at one end located within the bore of the band member and coöperating with said band member, the shank having a cylindrical part of reduced diameter embraced by the inner faces of the opposing projections, and the shank being provided with a threaded portion, and a nut for engaging the externally threaded projections and the shank to effect relative movement of the band and main members, said nut coöperating with one of the externally threaded projections and the threaded portion of the shank for uniting said projection and shank, substantially as and for the purpose described. 100 105 110 115

12. In an electrical coupling, a band member comprising two sections pivotally connected to each other at corresponding ends and provided at their opposite ends with opposing externally threaded projections, a main member having a shank provided with an engaging face at one end for coöperating with the band member, said projections being shaped to embrace a portion of the shank, and the shank being provided with shoulders projecting laterally beyond said projections, and being also provided with additional engaging means, and a nut for engaging the externally threaded projections and said shoulders to effect relative move- 120 125 130

ment of the band and main members, said nut coöperating with one of the externally threaded projections and the additional engaging means of the shank for uniting said 5 projection and shank, substantially as and for the purpose set forth.

13. In an electrical coupling, a band member comprising two sections pivotally connected to each other at corresponding ends 10 and provided at their opposite ends with opposing externally threaded projections substantially semi-cylindrical in cross section which in effect form a sleeve when the band member is in clamping position, contiguous 15 portions of the projections being provided with complementary recesses forming opposite slots opening laterally from the bore of the sleeve, and said projections having opposing lengthwise surfaces normally engaging 20 each other, a main member having a shank provided with a head at one end located within the bore of the band member and coöperating with said band member, the shank having a cylindrical part of reduced 25 diameter embraced by the inner faces of the opposing projections, and the shank being provided with shoulders projecting laterally through the recesses beyond said projections, and being also provided with a threaded 30 portion, and a nut for engaging the externally threaded projections and said shoulders to effect relative movement of the band and main members, said nut coöperating 35 with one of the externally threaded projections and the threaded portion of the shank for uniting said projection and shank, substantially as and for the purpose specified.

14. In an electrical coupling, a band member comprising two sections pivotally connected to each other at corresponding ends and provided at their opposite ends with opposing externally threaded projections of unequal length, a main member having a 45 shank provided with an engaging face at one end for coöperating with the band member, the shank being provided with additional engaging means, and said projections being shaped to embrace a portion of the shank, and a nut for engaging the externally threaded projections and the shank to effect relative movement of the band and main members, said nut coöperating with the externally threaded projection of greater 50 length and the additional engaging means of the shank for releasing the externally threaded projection of less length and uniting the projection of greater length to the shank, substantially as and for the purpose 55 described.

15. In an electrical coupling, a band member comprising two sections pivotally connected to each other at corresponding ends and provided at their opposite ends with

opposing externally threaded projections of unequal length, a main member having a shank provided with an engaging face at one end for coöperating with the band member, said projections being shaped to embrace a portion of the shank, and the shank 70 being provided with shoulders projecting laterally beyond said projections, and being also provided with additional engaging means, and a nut for engaging the externally threaded projections and said 75 shoulders to effect relative movement of the band and main members, said nut coöperating with the externally threaded projection of greater length and the additional engaging means of the shank for releasing the externally threaded projection of less length and uniting the projection of greater length to the shank, substantially as and for the purpose described.

16. In an electrical coupling, a band member comprising two sections pivotally connected to each other at corresponding ends and provided at their opposite ends with opposing externally threaded projections substantially semi-cylindrical in cross section 90 and of unequal length which in effect form a sleeve when the band member is in clamping position, contiguous portions of the projections being provided with complementary recesses forming opposite slots opening laterally from the bore of the sleeve, and said projections having opposing lengthwise surfaces normally engaging each other, a main member having a shank provided with a head at one end located within the bore of the band member and coöperating with said band member, the shank having a cylindrical part of reduced diameter embraced by 95 the inner faces of the opposing projections, and the shank being provided with shoulders projecting laterally through the recesses beyond said projections, and being also provided with a threaded portion, and a nut for engaging the externally threaded projections and said shoulders to effect relative 100 movement of the band and main members, said nut coöperating with the externally threaded projection of greater length and the threaded portion of the shank for releasing the externally threaded projection of less length and uniting the projection of greater length to the shank, substantially as and for the purpose 105 set forth.

17. In an electrical coupling, a band member comprising two sections pivotally connected to each other at corresponding ends and provided at their opposite ends with opposing externally threaded projections, a main member having a shank provided with an engaging face at one end for coöperating with the band member, said projections being shaped to embrace a portion of the shank, and the shank being provided with

lengthwise shoulders for coöperating with contiguous surfaces of the end of one of the externally threaded projections, and a nut for engaging the externally threaded projections and the shank, substantially as and for the purpose specified.

18. In an electrical coupling, a band member comprising two sections pivotally connected to each other at corresponding ends and provided at their opposite ends with opposing externally threaded projections, a main member having a shank provided with an engaging face at one end for coöperating with the band member, said projections being shaped to embrace a portion of the shank, and said shank being provided with additional engaging means and with lengthwise shoulders for coacting with contiguous surfaces of the end of one of the threaded projections, and a nut for engaging the externally threaded projections and the shank to effect relative movement of the band and main members, said nut coöperating with one of the externally threaded projections and the additional engaging means of the shank for uniting said projection and shank, substantially as and for the purpose described.

19. In an electrical coupling, a band member comprising two sections pivotally connected to each other at corresponding ends and provided at their opposite ends with opposing externally threaded projections, a main member having a shank provided with an engaging face at one end for coöperating with the band member, said projections being shaped to embrace a portion of the shank, and the shank being provided with shoulders projecting laterally beyond said projections, and being also provided with additional engaging means and with lengthwise shoulders for coacting with contiguous surfaces of the end of one of the threaded projections, and a nut for engaging the externally threaded projections and said shoulders to effect relative movement of the band and main members, said nut coöperating with one of the externally threaded projections and the additional engaging means of the shank for uniting said projection and shank, substantially as and for the purpose set forth.

20. In an electrical coupling, a band member comprising two sections pivotally connected to each other at corresponding ends and provided at their opposite ends with opposing externally threaded projections of unequal length, a main member having a shank provided with an engaging face at one end for coöperating with the band member, said projections being shaped to embrace a portion of the shank, and the shank being provided with additional engaging means and with lengthwise shoulders for co-

acting with contiguous surfaces of the end of the threaded projection of greater length, and a nut for engaging the externally threaded projections and the shank to effect relative movement of the band and main members, said nut coöperating with the externally threaded projection of greater length and the additional engaging means of the shank for releasing the externally threaded projection of less length and uniting the projection of greater length to the shank, substantially as and for the purpose described.

21. In an electrical coupling, a band member comprising two sections movably connected to each other at corresponding ends and provided at their opposite ends with opposing externally threaded projections, a main member having at one end an engaging surface for coöperating with the band member to clamp a conductor, the main member having an intermediate portion thereof interposed between opposing surfaces of the externally threaded projections, and a nut for engaging the externally threaded projections and said main member, substantially as and for the purpose specified.

22. In an electrical coupling, a band member comprising two sections movably connected to each other at corresponding ends and provided at their opposite ends with opposing externally threaded projections, a main member having at one end an engaging surface for coöperating with the band member to clamp a conductor, the main member having an intermediate portion thereof interposed between opposing surfaces of the externally threaded projections, said main member being provided with engaging means and with shoulders extending laterally beyond said projections and said engaging means, and a nut for engaging the externally threaded projections, the engaging means of the main member, and said shoulders, substantially as and for the purpose set forth.

23. In an electrical coupling, a band member comprising two sections movably connected to each other at corresponding ends and provided at their opposite ends with opposing externally threaded projections of dissimilar length, a main member having at one end an engaging surface for coöperating with the band member to clamp a conductor, the main member having an intermediate portion thereof interposed between opposing surfaces of the externally threaded projections, said main member being provided with engaging means, and a nut for engaging the externally threaded projections and the main member to effect relative movement of the band and main members, said nut coöperating with the exter-

nally threaded projection of greater length and said engaging means for releasing the externally threaded projection of less length and uniting the projection of greater length 5 to the main member, substantially as and for the purpose specified.

In testimony whereof, I have hereunto signed my name in the presence of two at-

testing witnesses, at Syracuse, in the county of Onondaga, in the State of New York, this 19th day of January, 1910.
